UNITED STATES PATENT OFFICE.

LOREN L. WHITNEY, OF HAMMOND, INDIANA, ASSIGNOR TO AMERICAN STEEL FOUNDRIES, OF CHICAGO, ILLINOIS, A CORPORATION OF NEW JERSEY.

METHOD OF FORMING FORGED FULCRUMS.

Application filed May 5, 1920. Serial No. 378,976.

To all whom it may concern:

Be it known that I, LOREN L. WHITNEY, a citizen of the United States, residing at Hammond, in the county of Lake and State 5 of Indiana, have invented certain new and useful Improvements in Methods of Forming Forged Fulcrums, of which the following is a specification.

This invention relates to a method of 10 making brake beam fulcrums.

The object of the invention is to simplify and improve the method of making brake beam forged fulcrums in a manner to reduce the cost and time of making the fulcrum, and in a manner to produce a fulcrum adapted to meet the requirements for successful commercial use.

This and other objects are accomplished by means of the method disclosed on the accompanying sheet of drawings, in which—

Figure 1 is a fragmentary perspective view of a blank in the form of a steel bar;

Figure 2 is a side view and Figure 3 a plan view of the same blank after it has 25 been provided with a loop portion under a drop hammer;

Figure 4 is a side elevation and Figure 5 a plan view of the same blank with a block inserted in the loop portion for building up the stock preparatory to providing the loop end with a tension rod seat;

Figure 6 is a side elevation and Figure 7 a plan view of the same blank after the tension rod seat has been formed; and,

Figure 8 is a fragmentary plan view of the completed fulcrum after the legs thereof have been bent into parallelism.

The various novel features of my invention will be apparent from the following 40 description and drawings and will be particularly pointed out in the appended claims.

Referring to the figures of the drawing, it will be noted that a blank 10 is first provided, which preferably is in the form of a steel bar. This bar is heated to a welding heat, especially at the middle section thereof, whereupon the blank is placed under a drop hammer and a loop 11 formed 45 in said blank at the middle portion by suitable drop hammer dies, it being noted that the leg portions 12 of the blank remain substantially in the same straight line with

the loop 11 offset with respect to said legs to form a pocket 13. A block of metal 14, 55 which is heated to a welding heat, is then inserted in the pocket 13 formed by the loop 11, as shown in Figures 4 and 5. The purpose of inserting this block 14 into the loop portion 11 is to build up sufficient stock 60 at the tension rod end preparatory to forming a tension rod seat in the fulcrum. After this block is inserted in the loop portion 11, the blank and the block are placed under a drop hammer and a tension rod seat 15 65 is formed by means of the drop hammer dies, said tension rod seat being shown in Figures 6 and 7. After the tension rod seat is formed, the fulcrum legs 12 are bent into parallelism to form the completed fulcrum, 70 as shown in Figure 8. It will be noted that the tension rod seat 15 extends diagonally with respect to the planes of the fulcrum legs 12 in order that the seat 15 may receive the horizontally arranged tension rod when 75 the fulcrum proper is turned to an angle to permit the slot 16 between the fulcrum legs 12 to receive an inclined brake lever.

By means of this method a fulcrum may be quickly and inexpensively made, the product being a fulcrum adapted to meet the requirements for successful commercial use.

It is my intention to cover all modifications falling within the spirit and scope of the following claims.

I claim:

1. The method of forming a fulcrum consisting in providing a blank, heating same, providing the blank with a curved offset loop portion at a point midway of its length, 90 inserting a piece of metal in the closed end of said loop portion to build up the stock at such point, and forming a tension rod seat at such built-up point.

2. The method of forming a fulcrum consisting in providing a blank, forming a curved offset loop portion therein at a point midway of its length, welding a block of material in the closed end of said loop portion to build up the stock, forming a tension rod seat in said built-up portion, and bending the legs of the fulcrum into parallelism.

Signed at Hammond, Indiana, this 29th day of April, 1920.

LOREN L. WHITNEY.
